TUFTING BUTTON

James A. Dayton, Litchfield, Conn., assignor to
 The Turner & Seymour Mfg. Co., Torrington,
 Conn., a corporation of Connecticut

Application July 9, 1947, Serial No. 759,831

3 Claims. (Cl. 24—90)

1

This invention relates to tufting buttons and the like, such as for use in tufting mattresses, cushions, etc., and more particularly to the construction of the shank and head of such a button and the anchorage therebetween.

In buttons of the type set forth, there is provided a head to which is secured a shank having a thread or cord receiving loop. In such buttons, the heads frequently fracture and the loops when formed with an open end under stress, may open, permitting escape of the thread or cord passing through the loop. Additionally, such open end may present sharp corners capable of cutting the fabric which is pierced by the loop and positioned between the loop and the underside of the head.

In the preferred form of tufting button of the present invention, the loop may be of any desired shape, and preferably provided with fabric engaging shoulders. The loop may be symmetrical and formed of half-round wire, the free ends of which are brought together to form a substantially cylindrical stem adapted to be secured in the button head. As an additional feature, the invention contemplates the securing of such cylindrical shank or stem thus formed within a head aperture of non-cylindrical or tapered bore by upsetting and expanding the shank within the aperture and riveting over the shank end on the outer surface of the button head. The invention further has to do with a head formed preferably of sheet metal, which is suitably rounded and shaped to eliminate sharp edges and to provide a neat appearance, the forming operation being such as to provide a proper shape of aperture for receiving the shank stem.

The above, and other features of the invention, will appear more fully from the following detailed description when taken in conjunction with the accompanying drawings. It is to be understood, however, that the drawings are employed for purposes of illustration only, and are not designed as a definition of the limits of the invention, reference being had for this purpose to the appended claims.

In the drawings, wherein like reference characters indicate like parts,

Figure 1 is a side elevation of a tufting button greatly enlarged with the head shown in section,

Figure 2 is a top plan view of the button, and

Figure 3 is a bottom view of the button head taken substantially on the section line 3—3 through the shank.

Referring to the drawings, the button will be seen to be composed of two elements, a head 10 and a shank 12. The head may be formed from

a thin disk of sheet metal having a center aperture punched therein, a rounded convex annular top surface 13, a dished central top portion 14, and a curved rimmed portion 15. The rim edge 6 is rounded as at 17 so as to avoid sharp edges which might otherwise tend to damage or cut the fabric with which the head is normally in contact.

The shank 12 has a loop portion which may 10 be of any desired shape, for example, that shown having converging side portions 16 and 18 terminating in a bight 20. This shape, however, is not a feature of the present invention, and may be varied at will to suit requirements. The upper portion of the loop may be bent inwardly as at 22 and 24, to form shoulders adapted to engage 15 the mattress ticking or cloth positioned immediately beneath the head, to prevent the button from becoming dislocated once it is positioned 20 within a mattress or cushion in the usual manner, well understood in the art.

The shank thus far described may preferably 25 be formed of so-called half-round wire so that the shoulder portions 22 and 24 may converge and be bent as at 26 and 28 to form a stem 30 of generally cylindrical outline by reason of the face-to-face engagement of the flat surfaces of the half-round wire, so that the stem will have a substantially smooth surfaced circular cross-section and thus not be liable to wear, pinch or tear the threads of the fabric through which it passes, despite the use of two adjacent wires in the stem, and despite their non-circular cross-section. Also, the shoulders 23, 24 will be positioned to present only the smoothly rounded surfaces of the wire to such fabric, and the corners of the shoulders will be rounded notwithstanding the use of wire of non-circular cross-section.

The button head may be formed by a single 35 punch and die operation from flat disks, the punch and die conforming closely to the shape of the head as previously described. The disk from which the head is formed, may be provided with a punched or otherwise formed substantially 40 cylindrical aperture which, when subjected to the dishing operation performed by the punch and die, will be caused to assume a tapered shape such as is indicated at 32. The dishing of the head to form the concave depression 14 results 45 in the stretching of the metal along the under-surface, thereby producing the conical or tapered bore 32. Also, through the application of a countersink punch during the same operation, an additional bevel 33 is formed, which facilitates the forming of said conical bore, and the

threading of the stem into the aperture. The cylindrical stem formed from the two half-round wire ends is positioned within the tapered hole 32 and by a swaging operation during which the exposed ends are supported and confined in suitable dies, the stem is upset and expanded into engagement with the conical wall of the aperture 32 and with a small annular shoulder formation engaging the beveled out portion 33 of the aperture, as is indicated at 34. The ends of the half-round wires are thereafter riveted over as at 36 to form in effect a single smooth, rounded stem head 38 which is well within the dished cavity portion 14 of the button head. The stem head 38, being below the level of the annular portion 13, will not interrupt the smoothness of the mattress or cushion surface, and any weight against the button will be largely carried by the smooth annular surface 13.

The stem as thus formed will be seen to be tightly locked within the tapered aperture in the button head, the upset portion of the shank 34 being expanded into complementary tapered engagement with the wall 32 of the tapered aperture in the button, and by reason of the riveted head 36, the button head is securely fastened to the shank.

There is thus described a tufting button in particular having a loop shank which is entirely closed and which may have any particular desired shape. In addition, the shank is securely fastened to the head so that detachment of the head from the shank or the loosening of the head upon the shank is practically impossible. The button so formed may be coated with paint or plastic or any desired substance to provide a pleasing appearance, or may be plated or otherwise treated. While the wire described from which the loop and shank is formed is preferably of half-round section, it will be appreciated that the angular edges between the flat and curved surfaces will be rounded as at 40, and it will also be appreciated that the shape may be varied from the true half-round in other ways without deviating in any substantial respect from the basic construction of the invention.

While the invention has been illustrated and described with respect to a specific form of tufting button, it is to be understood that the invention is not limited to a button used solely for tufting purposes, but may be embodied in other buttons or pronged elements having the fundamental features described. As changes in construction and arrangement may be made as will be appar-

ent to those skilled in the art after an understanding of the invention, reference will be had to the appended claims for a definition of the limits of the invention.

5. What is claimed and desired to be secured by Letters Patent is:

1. A button comprising in combination a disc-like sheet metal head which has an aperture therethrough, and a shank formed of a single piece of half-round wire shaped into a depending loop and with its ends brought together and upwardly directed from the loop flatwise in contact with one another to form a substantially cylindrical stem exposed beneath the button head, said 10 stem having an end portion passing up through said aperture and spread over to form of the two wire ends conjointly in effect a single stem head on the upper surface of the button head, the stem end portion being expanded within the aperture 15 to tightly engage the walls thereof, there being a small shoulder formation on said stem end portions and the button head being engaged between said formation and said stem head to rigidly affix the shank to the button head.

25. A button comprising in combination, a disc-like head, and a shank formed of a single piece of half-round wire shaped into a loop with the flat side of the wire innermost of the loop, the two ends of the wire being brought together and extending from the loop flatwise in contact with one another to form a stem with a neck portion of substantially circular cross-section, the end of said stem being rigidly engaged within said head.

30. A button in accordance with the foregoing claim 2 and in which the disc-like head has an aperture therethrough with downwardly divergent tapered walls, the stem end portion passing up through said aperture and tightly engaging said tapered walls and the upper end of said stem 40 being spread over to form a stem head at the upper surface of the button head.
